CLAIM

The ornamental design for a bezel, as shown and described in the figures.

DESCRIPTION

FIG. 1 is a front, top and right perspective view of a bezel showing my new design;

FIG. 2 is a front, top and left perspective view thereof;

FIG. 3 is a rear, top and right perspective view thereof;

FIG. 4 is a front plan view thereof;

FIG. 5 is a rear plan view thereof;

FIG. 6 is a left plan view thereof;

FIG. 7 is a right plan view thereof;

FIG. 8 is a top plan view thereof; and,

FIG. 9 is a bottom plan view thereof.
